UNITED STATES PATENT OFFICE.

JAMES McDERMOTT, OF NEW YORK, N. Y.

WAGON-BODY.

1,135,826.

Specification of Letters Patent. Patented Apr. 13, 1915.

Application filed March 9, 1914. Serial No. 823,855.

To all whom it may concern:

Be it known that I, JAMES McDERMOTT, a citizen of the United States, and a resident of the city of New York, Long Island City, 5 borough of Queens, in the county of Queens and State of New York, having invented a new and Improved Wagon-Body, of which the following is a full, clear, and exact description.

10 My invention relates to wagon-bodies of the build-up type.

An object thereof is to provide a simple, strong, convenient, and inexpensive wagon-body which can be easily and quickly assembled into a rigid structure and which can be used with animal or motor-propelled vehicles.

A further object of the invention is to furnish the trade with parts of a wagon-body which can be assembled or built up without the help of a blacksmith, and, furthermore, to provide a wagon-body any worn-out part of which can be easily and quickly replaced without the aid of a blacksmith.

A still further object of the invention is to provide a wagon-body the capacity of which may be varied. And another object of the invention is to provide a wagon-body where- 30 in members binding the different parts forming the wagon-body reinforce the same and constitute a means whereby said parts can be easily and quickly assembled or disassembled.

35 I attain these objects by the structure illustrated in the accompanying drawings forming part of the specification, in which similar characters of reference indicate corresponding parts in all the views and where- 40 in—

Figure 1 is a side elevation of an embodiment of my invention; Fig. 2 is a section on line 2—2, Fig. 1; Fig. 3 is a section on line 3—3, Fig. 1; Fig. 4 is a perspective view of 45 the rear of the wagon-body; Fig. 5 is a plan view of a fractional part of the wagon-body; Fig. 6 is a vertical section on line 6—6, Fig. 5; Fig. 7 is a side elevation of a wagon-body provided with a modified form of a retaining clamp; and Fig. 8 is a section on line 8—8, Fig. 7.

Referring to the drawings, the wagon-body is formed of a bottom 10, sides 11, and a front 12, the sides 11 as well as the front 50 12 being secured to the bottom and retained in place by means of retaining clamps 13

removably associated with transverse bars 14 forming part of the bottom 10, which bottom is preferably formed of a plurality of longitudinal members 15 between which are located a pair of structural iron members 16, preferably I-shaped beams, spaced from each other and which not only reinforce the bottom but form the slide strips generally used in the bottom of a wagon-body. The said longitudinal members 15 engaged by the I beam 16 are rigidly secured by any suitable means to the transverse bars 14, of which any number can be provided. As shown in the drawings, there are three 70 bars 14, the ends of which project from the bottom. When there are more than three longitudinal members in the bottom, the contacting edges of said longitudinal members are united by a tongue and groove joint, i.e., 75 the way the contacting edges of the boards 17 forming the sides are united.

Each of the sides 11 formed by the longitudinal boards 17 is framed by structural iron members which are preferably U-shaped 80 and of which the members 18 engage the upper and lower edge of the sides, and the members 19, that of the front and rear edges of the side. The U-shaped members 19 are engaged between the projecting ends of the 85 U-shaped members 18 which are bound to the longitudinal members forming the sides by means of bolts 20 passing through the U-shaped members and the boards, as best indicated in Fig. 3. These bolts bind the 90 structural iron members and the boards 17 together into a rigid structure; and in addition said bolts reinforce said structure, and by their location within the boards are protected from injury. The projecting ends 95 of the members 18 at the rear end of the wagon are preferably connected by a bolt 21 lying outside of the U-shaped member 19, the purpose being not only to reinforce the rear portion of the sides 11 but to use the 100 same, if desired, as means to where the rear end of the wagon-body may be removably connected. It is understood that the rear end may be connected in any other suitable customary way.

105 The sides 11 are supported by the projecting ends of the transverse bars 14 with their lower edge formed by the U-shaped member 18 resting on the metallic strips 22 provided between each of the transverse 110 bars and the longitudinal members forming the bottom, said metallic strips 22 extending

through the entire length of each of the transverse bars 14. The sides 11 are maintained in proper position by means of the retaining clamps 13 removably associated with the projecting ends of the transverse bars 14. Each of said retaining clamps 13 is provided with an apertured head portion 23. The aperture 24 of the head is angular in cross section and fits loosely on each end of the projecting ends of said transverse bars 14, which ends are of similar cross section to the aperture. The head 23 of each of the clamps is also provided with a set screw 25 adapted to engage the metallic strip 22 when the clamp is secured to the bar 14. Therefore the retaining clamp, which can only slide on the bar 14, is prevented from sliding by means of the set screw 25, whereby said clamp is maintained against the side 11 and said side against the edge of the bottom. The portion of the clamp 13 which extends transversely of the sides 11, and indicated by 26 in the drawings, is preferably U-shaped in cross section, as best seen in Fig. 4. The bottom of this U, which forms the extension, is provided with a series of apertures 27, through any one of which a bolt 28' may be passed to secure the same to any of the longitudinal members 17 forming the sides 11, and thus the retaining clamp is not only secured to the bottom, part of which is formed by the transverse bars, but also to the sides as stated.

The front 12 of the wagon is formed by boards 28 bound together by means of bolts 29 passing therethrough, similar to the manner in which the bolts 20 bind the boards 17 of the side. The lower edge of the front 12 is made to engage a U-shaped member 30 secured to the bottom (see Figs. 2, 5 and 6) and prevents the lower portion of said sides from moving between the sides 11 of the wagon. The upper portion of said side 12 is provided with members 31 each forming an eyelet through which a bolt 32 is made to pass, which bolt also passes through the sides 11 and the clamps 13, so that said bolt 32 forces the sides 11 against the front 12 and pins the same therebetween, thus preventing the movement of the upper portion of said front between the sides.

It will be noted that any stress applied to the sides 11 of the wagon-body will tend to force the same apart, and, therefore, the maximum reaction will take place at the portion of the transverse bars 14 projecting out of said sides; and by inserting the metallic strips 22 therebetween the tendency to break at this point is entirely eliminated.

In Figs. 7 and 8 a modified structure of the retaining clamp is shown whereby said sides 11' carried by said retaining clamp can be inclined with reference to the bottom within predetermined limits, whereby, also, the said side 11' can be varied in height.

The clamp 33, in this case, has its head 34 pivotally connected to the main body of the clamp, which main body 35 is similar in cross section to the portion 26 of the clamp 13 previously described. The pivotal connection obtained by means of a pin or bolt 36 permits the movement of the body in the longitudinal plane of the clamp. The lateral displacement of the head is prevented by extensions 37 formed by the head and engaging the sides of the main body portion of the clamp, as shown in Figs. 7 and 8. Projecting out of the upper end of the major portion 35 of the retaining clamp is a member 38 forming an extension of the clamp. The upper end of said member 38 is adapted to grip the upper edge of the side 11'. Said member 38 is provided with a longitudinal slot 39 which is engaged by the bolt 28' securing the side 11' to the retaining clamp. Said member, at its lower end, is also provided with a lateral extension 40 through which passes an adjusting screw 41, which also engages a projection 42 formed on the main body 35 of the retaining clamp 33. By means of such adjusting screws 41, the member 38 can be extended within a predetermined limit, and, thus the height of the side 11' can be varied by adding one or more of the boards 17. It is understood that in such cases the length of the bolts 20 binding said boards must be altered.

To give a proper inclination to the side 11', a proper size wedge 43 is fitted between the main body of the clamp 33 and the head 34 of the same, said wedge being retained in place by a recess 44 provided in the head. It is self-evident that the inclination may be increased or decreased by varying the size of the wedge 43. Thus, by means of this clamp 33, not only the inclination of the sides can be varied, but the length of the same can be increased very readily and without in any way reducing the strength of the entire wagon-body.

It will be seen that by providing a wagon-body as described, I can supply the trade with any part or all the parts of a wagon-body, and they can easily assemble the same. As, for example, I supply the sides and bottom all assembled and the only thing left for them to do is to put the retaining clamps 13 on to the projecting ends of the transverse bars 14 after the sides 11 have been placed. Or, if desired, the clamps can be secured to the sides 11 previous to their being mounted on the bottom by sliding the same into position with the heads of the clamps sliding on to the projecting ends, and then securing the clamps in proper position by tightening said screws 25. Thus, it will be seen that the wagon-body is formed by simply tightening the screws 25, then placing the front 12 into position and plac-

ing the bolt 32 to secure the front and the sides together. It will be seen that the assembling of the parts furnished will not require the services of a blacksmith, and that 5 if any additional bolts are to be placed to connect the sides 11 to the clamps 13, the holes can be drilled through the sides by anyone with a suitable tool.

It will be also noted that the capacity of 10 the wagon-body can be varied by means of inserting some of the boards 17 in the sides 11 of the wagon or by inclination of the sides by means of the modified structure of the retaining clamps.

15 It is evident that various changes might be made and modifications resorted to in the construction and arrangement of the parts described without departing from the spirit and scope of my invention; hence, I 20 do not wish to limit myself to the exact construction shown.

Having thus described my invention, I claim as new and desire to secure by Letters Patent:

25 1. In a wagon-body, a bottom comprising a plurality of longitudinal boards, spaced bars disposed transversely of said longitudinal boards, a metallic strip associated with each of said bars and positioned between 30 said bars and boards, said bars projecting from the sides of the bottom; sides adapted to rest on the projecting ends of said bars; and retaining clamps for securing said sides to the bottom, each of said retaining clamps 35 comprising an apertured head adapted to receive a projecting end of the bar and an extension adapted to engage the side, each of said clamps having means whereby the same can be rigidly secured to the bar and 40 side, substantially as and for the purpose set forth.

2. In a wagon-body, a bottom and sides forming independent units, said bottom having transverse bars projecting from the 45 sides thereof and forming a support for said sides; retaining clamps removably associated with the bottom and sides whereby said sides are maintained in proper position on the bars, each of said clamps comprising 50 an apertured head portion adapted to receive a projecting end of the bar and an extension U-shaped in cross section adapted to engage the side, said head portion having means whereby said clamp can be rigidly secured to said bars, and said extension having means in the bottom of the U portion whereby the same can be rigidly secured to the side, substantially as and for the purpose set forth.

60 3. In a wagon-body, a bottom and sides forming independent units, said bottom having transverse bars projecting from the

sides thereof and forming a support for said sides; retaining clamps removably associated with the bottom and sides whereby 65 said sides are maintained in proper position on the bottom, each of said retaining clamps comprising a main body and an apertured head pivotally connected, said apertured head being adapted to engage a projecting 70 end of the bar and having means for securing said head rigidly to the bar, said main body having means whereby the same can be secured to the sides; and wedges of different sizes adapted to be fitted between the 75 main body and the head of the clamp, whereby the inclination of the sides with reference to the body can be varied substantially as and for the purpose set forth.

4. In a wagon-body, a bottom and sides 80 forming independent units, said bottom having transverse bars projecting from the sides thereof and forming a support for said sides, and retaining clamps removably associated with the bottom and sides whereby 85 said sides are maintained in proper position on the bottom, each of said retaining clamps comprising a main body and an apertured head pivotally connected thereto, said head being adapted to engage a projecting end of 90 the bar; means whereby said head can be rigidly secured to the bar, said main body having means whereby the same can be secured rigidly to the sides, said head having a recessed portion; and wedges adapted 95 to be fitted into said recessed portion of the head and to engage said main body, whereby the inclination of the sides with reference to the bottom of the wagon can be varied.

5. In a wagon-body, a bottom and sides 100 forming independent units; retaining clamps removably associated with the bottom and sides whereby said sides are maintained in proper position on the bottom, each of said 105 clamps comprising an extension at the upper end thereof, said extension having a U-shaped portion at one end adapted to engage the upper edge of the sides, and a lateral extension at the lower end, said clamp having a projection; and a screw engaging the lateral projection of the extension and the projection of the clamp, whereby the length of the clamp by means of said extension can be varied, said extension having a longitudinal slot whereby the same can be adjusted 110 and rigidly secured to the clamp.

In testimony whereof I have signed my name to this specification in the presence of two subscribing witnesses.

JAMES McDERMOTT.
